UNITED STATES PATENT OFFICE.

JESSE SNYDER, OF CHICAGO, ILLINOIS.

VENTILATOR.

Application filed May 28, 1928. Serial No. 281,132.

This application is a continuation in part of my U. S. application Serial No. 249,743, filed January 26th, 1928, and allowed April 5th, 1928.

The invention relates to improvements in ventilators of the type to extend across the lower portion of a window frame to admit fresh air when the lower sash of the window is partly raised. The ventilator is provided with a cover preferably having openings covered with fine screen wire to prevent entrance of dust and the like, and it is the principal object of my invention to provide novel mounting means for this cover, permitting it to be moved inwardly and downwardly and suspended in a substantially vertical position at the inner side of the ventilator body, when its use is not desired, and permitting said cover to be totally detached whenever desired.

Further objects are to provide a cover of simple and inexpensive, yet strong and durable construction, securing a sheet of woven wire in place in a unique manner, and to also provide the cover with such construction as to readily secure a rubber or other flexible strip thereto, for contact with the lower window sash.

With the foregoing in view, the invention resides in the novel subject matter hereinafter described and claimed, description being accomplished by reference to the accompanying drawing.

Fig. 1 is a horizontal sectional view through a window illustrating a top plan view of the ventilator.

Fig. 2 is an inner side elevation of the parts shown in Fig. 1.

Fig. 3 is a vertical transverse section as indicated by lines 3—3 of Figs. 1 and 2.

Fig. 4 is a fragmentary end elevation illustrating the manner in which the ventilator cover may be moved inwardly and downwardly and suspended in a substantially vertical position.

Figs. 5 and 6 are enlarged detail longitudinal sectional views on lines 5—5 and 6—6 respectively, of Fig. 1.

Fig. 7 is a disassembled perspective view of portions of the cover.

In the drawings above briefly described, the numerals 8 denote two substantially triangular end members preferably formed of metal and adapted to be secured by screws or other means 8^a to opposite sides of a window frame, at the inner side of the lower

sash S. Extending between the end members 8 is an inwardly inclined inner wall 8^b which is preferably formed of glass with its ends held between flanges 8^c on said end members, said wall 8^b and said end members 8 forming a ventilator body of substantially the same construction as those now in common use.

A cover 9 rests normally upon the wall 8^b and the end members 8, said cover embodying upper and lower sheet metal plates 10 and 10^a having air inlet openings 11 which are covered with screen wire 12 held between said plates. The inner edge of the plate 10 turns downwardly as at 13, providing a flange disposed at the inner edge of the cover 9 to engage the wall 8^b, while the outer edge of said cover is provided with a yieldable strip 14 of rubber or other desired material, to engage the sash S.

Between their longitudinal edge portions, spacing means are provided for the plates 10—10^a, said spacing means being shown in the form of bosses 10^b stamped upwardly from the plate 10^a and spot-welded to the plate 10, as at 10^c. This construction is simple and easy to manufacture, yet with light sheet material for the plates 10—10^a, so connects them as to provide a rigid cover structure. The sheet of screen wire 12 may be inserted between the two plates after they have been welded together as they are held in sufficiently spaced relation to readily permit inward sliding of said sheet.

At their outer longitudinal edges, the plates 10—10^a project beyond the wire sheet 12 as indicated at 14^a and 14^b respectively. The inner portion of the flexible strip 14 is received between the plate portions 14^a—14^b and is provided with a longitudinal bead 14^c. This bead is received in a groove 14^d formed by stamping the plate portion 14^b. The bead 14^c may be molded upon the strip 14 or may be formed by bending an edge portion of this strip around a wire 14^e. In either instance, the strip 14 will be tenaciously anchored between the plates 10—10^a, yet may be removed, should age dictate that a new strip be substituted.

Short metal channel bars 15 receive and are secured by rivets 15^a to the ends of the plates 10—10^a, each of these bars being provided with an upstanding ear 16 at its intermediate portion struck outwardly from its lower flange and its vertical, flange-connecting portion. Two outwardly inclined links 17, dis-

posed at the outer sides of the end members 8, have their upper ends pivoted at 17^a to these ears 16, while combined pivotal and slidable connections are provided between the lower ends of the links 17 and the end members 8. These connections consist of slots 18 formed in the links 17, and bolts or the like 19 passing loosely through said slots and secured in openings in the end members 8. The slots 18 of the links 17 are formed with lateral throats 18^a. When the cover is moved to a position permitting vertical disposition of the links, these throats 18 may be alined with the bolts or the like 19, permitting disconnection of said links from the bolts and consequently permitting the entire cover to be removed.

The construction above described, permits movement of the cover 9 from its normal horizontal position, inwardly and downwardly, until it occupies a substantially vertical position at the inner side of the wall 8^b, in which position it is suspended by the links 17, as seen in Fig. 4. In order to permit easy movement of the cover to this position or return to its normal position, it is preferably provided with appropriate knobs 20.

On account of the existing advantages for the details disclosed, they are preferably followed. However, within the scope of the invention as claimed, variations may be made.

I claim:—

1. A ventilator comprising a body having an inner wall to span the lower portion or a window frame, and end members at the ends of said wall for connection with the frame sides; a cover resting on said body, links at the outer sides of said end members extending across the innermost upper corner portions thereof, means pivoting the upper ends of said links to the ends of said cover, the lower portions of said links being provided with longitudinal slots having lateral throats opening through one edge of the links and studs projecting outwardly from said end members and received in said slots, said links permitting movement of the cover from a horizontal to a vertical position, said throats permitting disconnection of the links from said studs when the links are moved to aline said throats and studs.

2. A ventilator comprising a body having an inner wall to span the lower portion of a window frame and end members at the ends of said wall for connection with the frame sides; a cover resting on said body, said cover comprising a sheet metal plate, a downwardly extending flange on the inner edge of said cover plate to engage the inner side of said inner wall of the body, metal bars secured upon and extending across the ends of said cover plate, ears formed on and projecting upwardly from said bars, outwardly inclined

links at the outer sides of said end members and extending across the innermost corner portions thereof, said links having their upper ends pivotally connected with said ears, and provided in their lower portions with longitudinal slots having lateral throats opening through one edge of the links, and headed studs projecting outwardly from said end members and received in said slots, said links permitting movement of the cover from a horizontal to a vertical position, said throats permitting disconnection of the links from said studs when the links are moved to aline the said throats and studs, the heads of the studs preventing outward springing or lateral disengagement of the links from the studs.

3. In a ventilator, two plates having registering openings, spacing means near the edges of the plates holding said plates in closely spaced parallel planes, a sheet of screen wire in the space between said plates and extending across said openings, and channel-shaped end bars receiving and secured to the ends of said plates.

4. In a ventilator, two sheet metal plates having registering openings, one of said plates having bosses stamped thereon near its edges, the other plate being secured against said bosses, whereby the two plates are held in spaced parallel planes, a sheet of screen wire in the space between said plates and extending across said openings, and channel-shaped end bars receiving and secured to the ends of said plates.

5. In a ventilator, two sheet metal plates having registering openings, one of said plates having bosses stamped thereon near its edges, and welded to the other plate, whereby the two plates are held in spaced parallel planes, a sheet of screen wire in the space between said plates and extending across said openings, and channel-shaped end bars receiving and secured to the ends of said plates.

6. A structure as specified in claim 3; together with ears stamped from one flange of said end bars and the flange-connecting portion of said bars, said ears projecting laterally from the other flange of said bars.

7. In a ventilator, a sheet of screen wire, two apertured plates secured against opposite sides of said wire sheet and projecting beyond an edge thereof, the projecting portion of at least one of said plates having a longitudinally extending groove stamped therein, and a sash-engaging flexible strip having a portion held between said extended plate portions, said strip portion having a bead held within said groove.

In testimony whereof I have hereunto affixed my signature.

JESSE SNYDER.
